UNITED STATES PATENT OFFICE

2,506,709

AUTOMATIC EMERGENCY MECHANISM

Joseph A. Donnelly, Pittston, Pa.

Application February 19, 1948, Serial No. 9,444

7 Claims. (Cl. 246—171)

1

This invention comprises novel and useful improvements in an automatic emergency mechanism and more specifically pertains to an emergency device for automatically applying the air brakes of a train whenever a wheel jumps the rail; and whenever one or more bearings become overheated.

The principal object of this invention is to provide an attachment which may be readily applied to railway trains and to the air brake system thereof, for automatically venting the train line pressure and applying the air brakes whenever a wheel jumps the rail.

A further object of the invention is to provide an attachment in accordance with the preceding object which will further apply the air brakes whenever one of the journals becomes overheated.

An important feature of the invention resides in providing an attachment which may be readily applied to and mounted on the journal box of a railway truck and which is connected to the train pipe and the train line pressure thereof.

A further feature of the invention resides in the provision of an attachment as set forth in the preceding objects and features together with an actuating means for venting the train pipe by engagement of a valve actuating lever with the rail whenever a wheel jumps the rail.

And a further feature of the invention is to provide an improved means for positively opening or venting the train pipe whenever a wheel of a truck jumps the rail.

These, together with various ancillary objects of the invention which will later become apparent as the following description proceeds, are attained by this device, a preferred embodiment of which has been illustrated by way of example only in the accompanying drawings, wherein:

Figure 1 is a side elevational view of a portion of a railway car truck, partly in section and partly in elevation and taken substantially in the plane of the vertical section line 1—1 of Figure 2, showing the invention applied thereto;

Figure 2 is a top plan view of the invention as applied to a railway car truck as shown in Figure 1;

Figure 3 is an enlarged detailed view partly in vertical elevation and partly in vertical section through the venting valve means of the device;

Figure 4 is a vertical transverse detailed sectional view taken substantially in the plane of the section line 4—4 of Figure 3;

Figure 5 is a vertical transverse sectional de-

2

tailed view taken substantially in the plane of the section line 5—5 of Figure 3;

Figure 6 is a broken longitudinal sectional view through the temperature responsive air venting means of the invention;

Figure 7 is a fragmentary perspective view of a detail of the invention;

Figure 8 is a perspective view of a cam for operating the venting valve of the invention;

Figure 9 is a top plan view, parts being broken away of the thermostatically controlled venting valve of the invention;

Figure 10 is an enlarged view taken in top plan substantially upon the plane of the horizontal section line 10—10 of Figure 3; and

Figure 11 is an elevational end view of the thermostatic valve means shown in Figures 6 and 9.

Referring now more specifically to the accompanying drawings, wherein like numerals designate similar parts throughout the various views, attention is directed first to Figures 1 and 2, wherein 10 indicates generally a portion of the frame of a railroad truck of any conventional type, which frame is provided with the customary journal box 12 within which is mounted the journal bearing 14 for supporting the weight of the railway car and truck upon the axis 16 of a wheel 18 mounted in the usual manner for rolling movement upon a roadbed rail 20.

As shown best in Figure 1, a branch conduit 22 preferably of a flexible nature is connected with the main train line pipe for supplying air pressure for operating the air brakes of the train, which branch pipe is connected to a T-coupling 24, having forwardly and rearwardly extending branches 26 and 28. One of these branches as 26, is connected with a thermostatically controlled valve means to be described hereinafter for venting the train line pressure and therefore adjusting or setting the air brakes of the train in a slow serviceable position thus bringing the train to a slow and normal stop when the bearing journal 14 exceeds a predetermined safe temperature. The other conduit 28 is connected with a venting valve indicated generally at 30 which is operable whenever the wheel 18 jumps or drops from the rail 20 to immediately set the brakes of the entire train in emergency position for stopping the train. The T-shaped coupling 24 and branch conduits 26 and 28 may be mounted upon the journal box 12 in any suitable manner. However, in order to render the device readily applicable to existing journal boxes of railway trucks, there is provided a mounting bracket 32

which is generally square or rectangular in shape as shown in Figure 1 and may be readily applied to and clamped about conventional types of journal boxes as by a clamping nut and bolt 34.

It is contemplated that all of the parts forming elements of this attachment may be rigidly secured as by welding to the outer surface of the strap or clamp 32, whereby the entire device as a unitary assembly may be readily applied to or removed from a journal box of a conventional truck journal.

As shown in Figure 1, the T-shaped coupling 24 is secured as by a web or supporting flange 36 which is welded to the upper surface of the strap 32.

Attention is now directed more particularly to Figures 6 and 9 for a better understanding of the construction of the thermostatically operated venting valve forming a part of this invention. A tubular sleeve or bushing 38 which is externally threaded as at 40, is inserted in an opening in the end wall of the journal box 12, and has its forward extension 42 which is of square cross-section as shown in Figure 11, and closed at its inner end as at 44, inserted in a suitable bore in the upper portion of the journal box with its end in close and direct contact with the bearing journal 14. As will be seen by reference to Figures 6 and 9, the end or terminal of the bushing 40 is provided with a plurality of longitudinally spaced bores or apertures 46, which are filled or closed by fusible plugs 48 of any suitable material such as alloys having different melting points.

The thermostatic element 38 is retained in proper position as by fastening nuts 50 which embrace the end wall of the journal box 12 in order to rigidly secure the thermal element in proper position in the journal box.

The operation of the thermally responsive venting means is as follows. Brake pipe pressure is constantly supplied by the flexible conduit 22, the T-shaped coupling 24 and the branch conduit 26 to the interior of the thermal element 38. When a hot box develops, or the bearing journal 14 attains a temperature exceeding a predetermined safe maximum for which the thermal element is adjusted, one or more of the low melting point alloy fusible plugs 48 will be melted, thereby establishing a vent for the brake pipe.

As set forth hereinbefore, each of the plugs 48 may have a different melting point, whereby successive vents will be established, as the temperature of the journal bearing begins to rise. Thus, as the temperature rises, the leak of the air from the air pipe will be gradually increased, thus gradually applying the brakes until when all of the fusible plugs have been melted, a sufficient leak is established to slowly and serviceably set the brakes of the entire train and thereby bring the train to a slow and normal stop. Alternatively, all of the plugs 48 could be of the same material, whereby as the temperature of the journal exceeds its predetermined safe minimum, the heat will travel from the closed end 44 backwardly along the thermal element, melting one fusible plug after another until the entire air pressure of the main train line is exhausted. There is customarily a shut-off valve between the train line and the flexible conduit which it is necessary to close in order to restore the air brake system to operative condition. The thermal unit 38 which has been vented by overheating the bearing must be replaced by a new unit.

Attention is now directed to Figures 1-3 for an understanding of the mechanism for setting the

brakes in response to a wheel jumping the track. As shown in Figure 3, the branch line 28 is externally threaded at its outer extremity as at 52. A generally cylindrical bushing or sleeve 54 is screwed upon the threads 52, this bushing being provided at its outer end with a valve seat or port 56. A generally circular plate 58 having a valve disk 60 secured thereto as by an integral threaded stem 62 and lock nut 64, is pivotally secured to the casing 54. To effect this, the plate 58 is provided with apertures at its lower and upper portions, through which extend rods 66 and 68 respectively, these rods being pivoted at their inner ends as at 70 and 72 to lugs 74 and 76 on the housing 54.

The lower rod 66 is thus pivoted to the lug 74 at its inner end, while its outer end is screw-threaded as at 78, extends through the lower aperture in the plate 58 and is adjustably positioned therein as by the outermost adjusting nut 80.

The lowermost rod 66 is thus pivoted about its pin 70, and constitutes an adjustable fulcrum for the plate 58. The adjustment of this fulcrum is regulated by adjustment of the nut 80 upon the screw-threaded portion 78 of the rod 66, to thus adjust the fulcrum longitudinally of the rod 66. The upper rod 68 constitutes a latch means for retaining the valve plate 58 in its closed position. For this purpose, the rod 68 is provided with an outer screw-threaded portion 82, upon which are provided adjusting nuts 84 and 86 which are adapted to straddle the aperture at the upper end of the valve plate 58, this aperture being indicated at 88 as forming a vertically extending notch or detent. When the valve plate 58 is closed, with the valve 60 being pressed against the seat 56, with or without the aid of a gasket for establishing an air-tight seal at this point, the plate is retained in its closed position by means of the lock nuts 84 and 86 straddling the aperture 88 in the plate 58. When, now, the rod 68 is raised upwardly about its pivot pin 72, the lock nuts 84 and 86 will be withdrawn from their retaining engagement with the notch 88, thereby releasing the upper end of the plate 58 and permitting the same to pivot or swing outwardly and thus permit the valve 60 to uncover the port 56. When this occurs, a complete venting of the train line is effected, this reduction of pressure causing an immediate setting of the brakes of the train to the emergency position. This upward movement of the latch rod 68 is effected by means of a push rod 90 which as shown in Figure 1, is journalled for vertical movement in a suitable guide bushing or bracket 92 carried by the strap 32. The upper end of the push rod 90 as shown more clearly in Figures 3 and 10, is provided with a semi-circular seat 93 engaging the undersurface of a curved semi-circular seat 94 in a member 96 screw-threaded upon the outer extremity of the rod 68.

The lower end of the push rod 90 is pivoted as at 98 to an operating lever 100 which is pivoted as at 102 to a support bracket 104 welded or otherwise attached to the lower portion of the clamp 32. The lever 100 extends through a pair of guide members 106 and 108 depending from the strap 32, to confine the lever to movement in a vertical plane.

The innermost end of the lever 100 is provided with a curved portion 110 constituting an abutment element for engagement with the undersurface of the strap 32, to limit the swinging of

the lever about its pivot 102 in a counterclockwise direction.

The outer end of the lever as shown best in Figure 2, is provided with an inwardly curved portion 112 terminating in an end portion 114 which overlies the rail 20. Secured to the outer end of this terminal portion 114, is a contact member 116 which overlies the rail 20 and is spaced slightly thereabove. The arrangement is such that when the wheel 18 jumps the rail 20, the wheel will drop down upon the tie of the roadbed, causing the contact member 116 to drop upon the rail 20, and urge the lever 100 in a clockwise direction about its fulcrum end 102, thereby lifting the push rod 90 and causing the members 92 and 96 to raise the latch 68, thereby releasing the upper end of the valve plate 58. As above described, this causes the valve plate to pivot about its fastening at the outer end of the lower rod 66, thereby opening the valve 60 from its seat 56 and venting the train line pressure to set the brakes of the train.

As so far described, this device is perfectly capable of satisfactory operation under normal conditions. However, in some instances, particularly in below freezing temperatures, it is possible that moisture may freeze upon the valve and its seat, whereby the train line pressure will be insufficient to break this engagement and vent the train line, when the rod 90 is elevated. In order to prevent this condition, positive means are provided for forcing the valve from its seat upon an actuation of the rod 90. This means as shown most satisfactorily in Figures 3, 4 and 5, consists of a pair of cams 118, pivoted as at 120 to the sides of the casing 54, and provided with operating arms 122, which are provided with notches 124 in the ends thereof. As shown in Figures 3 and 7, the rod 68 has welded thereto a pair of arcuate laterally disposed arms 126, whose lower ends are provided with inturned portions 128, adapted to engage the notches 124. The arrangement is such that when the latch 68 is elevated or lifted about its fulcrum pin 72, the arms 126 and ends 128 are likewise lifted, the latter engaging the notches 124, and rotating the cam 118, to cause the nose thereof to force the plate 58 away from the end of the casing 54 and thus positively retract the valve 60 from its seat 56.

From the foregoing, the construction, operation and advantages of the invention will be readily understood, and accordingly further explanation is believed to be unnecessary. However, since numerous changes will readily appear to those skilled in the art, it is not intended to limit the invention to the exact construction described, but all suitable modifications and equivalents may be resorted to falling within the scope of the appended claims.

Having described the invention what is claimed as new is:

1. In combination with a railway train air brake system, a railway truck, a safety device including a pressure release valve assembly connected with the train line and operable to vent the same for setting the train brakes in response to derailment of said railway truck, said valve assembly having a casing with a valve seat, a valve cooperating with said seat for controlling

the venting of the train line, a fastener pivotally mounting said valve upon said casing, a latch pivoted to said casing and releasably retaining said valve upon its seat, an actuator for said latch operable in response to derailment of said truck for disengaging said latch from said valve, a valve operating means actuatable by said actuator for positively moving said valve from its seat.

10 2. The combination of claim 1 wherein said valve operating means includes a cam operatively connected with said valve for forcing the latter from its seat.

15 3. The combination of claim 1 wherein said valve operating means includes a cam operatively connected with said valve for forcing the latter from its seat, said cam being mounted on the exterior of said casing and being connected to said latch for operation thereby.

20 4. The combination of claim 1 wherein said valve operating means comprises a lever pivoted to said casing, a cam portion on said lever engageable with said valve for moving the same from its seat upon oscillation of said lever and a link connecting said lever and latch for simultaneous movement by said actuator.

25 5. In combination with a railway train air brake system, a railway truck, a safety device including a pressure release valve assembly connected with the train line and operable to vent the same for setting the train brakes in response to derailment of said railway truck, said valve assembly having a casing with a valve seat, a valve cooperating with said seat for controlling the venting of the train line, a fastener pivotally mounting said valve upon said casing, a latch pivoted to said casing and releasably retaining said valve upon its seat, an actuator for said latch operable in response to derailment of said truck for disengaging said latch from said valve, a valve operating means actuatable by said actuator for positively moving said valve from its seat, a journal box on said truck and means for detachably mounting said safety device upon said journal box.

30 6. The combination of claim 5 wherein said last means includes a strap, means for clamping said strap upon said journal box, and means for securing said casing and said actuator to said strap.

35 7. The combination of claim 5 wherein said last means includes a strap, means for clamping said strap upon said journal box, and means for securing said casing and said actuator to said strap, the casing being mounted upon the upper surface of the strap and the actuator being secured to the lower surface of the strap and depending therefrom.

JOSEPH A. DONNELLY.
